ELECTRICIAN'S FLEXIBLE CONDUIT PULLER ATTACHMENT

Harold L. Moldt, Jr., 1809 Rhomberg Ave.,
Dubuque, Iowa

Filed Apr. 15, 1964, Ser. No. 79,507

Term of patent 14 years

(Cl. D26—1)

Fig. 1

Fig. 2

Fig. 3

FIG. 1 is a perspective view of an electrician's flexible conduit puller attachment, showing my new design;

FIG. 2 is a side elevational view, the opposite side being substantially a mirror image thereof; and

FIG. 3 is a top plan view, the bottom being substantially a mirror image thereof.

The left end in FIGS. 2 and 3 is a slightly convex, unornamented surface.

I claim:

The ornamental design for an electrician's flexible conduit puller attachment, as shown and described.
